(57) **CLAIM**

The ornamental design for a toy and storage assembly, as shown and described.

DESCRIPTION

FIG. 1 is a front view of a toy and storage assembly with the lid to the chest closed;

FIG. 2 is a perspective view thereof with the lid to the chest opened, showing the internal chest;

FIG. 3 is a back view thereof with the lid to the chest closed;

FIG. 4 is back view thereof with the lid to the chest opened;

FIG. 5 is a side view thereof with the lid to the chest closed;

FIG. 6 is an opposite side view thereof with the lid to the chest opened, showing the internal chest;

FIG. 7 is a bottom view thereof; and,

FIG. 8 is a perspective view thereof, with a pillow head attached.

In FIG. 8, the broken lines showing of environmental structure for purposes of illustrating the toy and storage assembly in a condition of use. The broken lines and the structure they depict form no part of the claimed design.
